ABSTRACT

A transducer is formed of a thin sheet of electrostrictive material having opposing faces with electrodes disposed over the opposing faces. At least one of the electrodes has a substantial resistance measurable between a pair of spaced points on the electrode.

RESISTIVE ELECTRODE FOR AN ELECTROSTRRICTIVE TRANSDUCER

This is a continuation of application Ser. No. 142,510, filed May 12, 1971, which in turn is a continuation in part of application Ser. No. 790,091, filed Jan. 9, 1969, now abandoned.

BACKGROUND OF THE INVENTION

Electrostrictive transducers are formed of a thin sheet of electrostrictive material having conductive electrodes on opposing faces. A signal is applied to the opposing electrodes to cause mechanical movement of the transducer. Since the transducer consists of parallel conductive plates separated by a dielectric, the load presented by the transducer is capacitive and the transducer is frequency responsive. For example, a 100:1 variation in frequency of the signal applied to the transducer will produce approximately a 100:1 variation in the input impedance of the transducer. This variation of input impedance with frequency causes a large variation in the output of the transducer with frequency.

SUMMARY OF THE INVENTION

It is, therefore, an object of this invention to provide an electrostrictive driver having an improved frequency response.

It is another object of this invention to employ frequency dependent attenuation to vary the effective amount of an electrostrictive transducer used in operation at different frequencies.

In practicing a preferred embodiment of this invention a transducer is provided including a thin sheet of ceramic material having opposing faces. The transducer includes electrodes disposed on the opposing faces with one of the electrodes being conductive and the other being resistive relative to the conductive electrode. The resistive electrode acts to improve the frequency response of the driver by causing increasing attenuation of signals with increasing frequencies thereby changing the active area of response of the driver with frequency. The transducer may also have both electrodes formed of resistive material or the electrodes may be formed with both resistive and conductive portions. By mechanically loading or driving the transducer at or near the point of electrical connections to the electrodes, the optimum frequency response of the transducer is obtained.

BRIEF DESCRIPTION OF THE DRAWING

The invention is illustrated by the drawing of which: FIG. 1 is a schematic of the equivalent circuit of a prior art transducer;

FIG. 2 is a view of the structure of a transducer of a preferred embodiment of this invention;

FIG. 3 is a schematic diagram of the equivalent circuit of the structure of FIG. 2;

FIGS. 4 and 5 are views of the structure of second and third embodiments of the invention;

FIG. 6 is a sectional view of the structure of FIG. 5; and

FIG. 7 is a view of a loudspeaker structure incorporating the features of the transducer structure of this invention.

DETAILED DESCRIPTION OF THE INVENTION

A prior art transducer has the equivalent circuit shown in FIG. 1. Since the transducer consists of di-

electric material separating two conductive plates, the ceramic transducer presents a largely capacitive input impedance which is represented by capacitor 10. Since the impedance of a capacitor varies indirectly as the frequency of the signal applied thereto, the input impedance of the prior art driver circuit will vary in the same ratio as the frequency of the driving signal. That is, for a 100:1 range in the frequency of the driving signal the input impedance will vary over a range of 100:1.

10 An improved transducer structure using, for example ceramic material, reduces the variation of input impedance with driving frequency and is shown in FIG. 2. The structure includes a sheet of ceramic material 12 having electrodes 13 and 14 on opposing faces thereof.

15 A metal sheet 15 is cemented to one side of the transducer to provide for motion in a bending mode as shown. The driving signal is applied to terminals 16 and 17 which are connected to the electrodes through wires 18 and 19. One end of the transducer is fastened to a mass 21 which prevents movement of the end of the transducer attached thereto. The other end of the transducer is free to move and is coupled to a speaker 23. While the transducer is shown as being coupled to speaker 23 it may, of course, be coupled to any other device which it is desired to drive.

20 Electrode 14 consists of two portions, a relatively resistive portion 25 as compared with the electrode 13 and a relatively conductive portion 26. The conductive portion 26 is at one end of the transducer and is used to make contact between the wire 19 and the resistive portion 25.

25 FIG. 3 shows the equivalent circuit of the structure of FIG. 2. In FIG. 3 the capacitance presented by the ceramic dielectric separating two electrodes, such as the electrodes 13 and 14, is a distributed capacitance 10a combined with a resistive element 11. Since the impedance presented by a resistor is linear with respect to frequency variation, the resistance acts to reduce the variation of the input impedance of the ceramic transducer with frequency. The amount of reduction of the variation of the input impedance is determined by the value of the resistance of the resistor 11 (in turn determined by the characteristics of the electrode 25) and the dielectric constant and thickness of the ceramic which establishes the value of the distributed capacitance 10a.

30 Electrode 25 may have a uniform resistivity or the resistivity may vary with position on the transducer as desired. While only electrode 14 is shown as being resistive in FIG. 2, it is, of course, possible to make both electrodes 13 and 14 resistive. Examples of materials found useful for constructing the resistive electrode 25 are graphite or a very thin layer of deposited nickel (of the order of 0.1 mils thick). However, the resistive electrode is not limited to these materials but exhibits a higher resistance than the resistance of the conductive electrode 13.

35 In a structure of the type shown in FIG. 2 the input terminal 16 is coupled to electrode 14 at the free end or radiating portion of the ceramic transducer. The free portion of the transducer is more responsive to high frequencies than is the fixed end of the transducer. By coupling the input signal to the free end of the transducer to which the speaker 23 also is mechanically coupled, a further improvement is made in the response of the transducer. Since the resistive path in combination with the parallel capacitance has a greater attenuating

effect on high frequency signals than on low frequency signals, the high frequency energy is concentrated in the region near the free end of the driver and acts upon that portion of the driver only. Thus, only the portion of the driver near the free end vibrates or is active at high frequencies. As the frequency becomes lower, more and more volume of the driver becomes active and appears as a load across the driving source. This further acts to reduce the variation in transducer impedance presented to the source of input signals.

The structure of FIG. 2 may be constructed in the form of a circular disc as shown in FIG. 4. FIG. 4 shows one surface of the ceramic driver having conductive electrodes 28 and 29 separated by resistive electrode 30. In this structure the disc would be supported along the edges with the center free to vibrate.

The other surface of the ceramic driver of FIG. 4 could have an electrode arrangement of the type shown for electrodes 28, 29 and 30 or could comprise a homogeneous conductive electrode comparable to the conductive electrode 13 shown in the embodiment of FIG. 2. The electrical input connections then could be made to the center electrode 28 and the center of the electrode on the other side of the disc, if a resistive electrode comparable to the electrode 30 is used on that side, or to any point on the opposite side of the disc if a conductive electrode is used on that side of the disc. A pair of discs then can be cemented together to form a bimorph transducer or a single disc could be prestressed in a dish-shaped configuration and polarized to operate as a monomorph driver.

The apex of a speaker cone such as the speaker 23 is connected to the center of the disc, with the vibration of the disc being restricted to different areas of the disc, as indicated by the dotted lines in FIG. 4, in accordance with the driving frequency applied across the electrodes at the center of the disc. For example, for input signals of the highest frequencies, the innermost dotted ring encloses the area actively employed in driving the speaker attached to the center of the disc, with the remainder of the disc remaining relatively inactive due to the attenuation of the input signals provided by the low-pass R-C filter circuit resulting from the use of the resistive electrode 30. This R-C filter circuit is comparable to the one shown in FIG. 3.

As the input frequency is reduced, a greater area of the disc becomes active in vibrating and driving a mechanical load attached to the center of the disc, with these greater areas being indicated by the center and outermost dotted circles in FIG. 4. For very low frequencies, the R-C attenuation is practically zero; so that the entire mass of the disc vibrates to drive a mechanical load attached to the center of the disc.

In operating a transducer of the type shown in FIG. 4, either as part of a bimorph driver or as a monomorph driver, the resistivity required for the relatively resistive conductor 30 varies in accordance with the particular type of material used for the electrostrictive element, since this material forms the dielectric of the capacitor formed between the electrodes on both sides of the transducer. For electrostrictive materials having a very high dielectric constant, the resistive electrode 30 can have a lower unit value of resistance than for materials exhibiting a very low dielectric constant. In addition, the thickness of the dielectric material is an important factor. As the thickness of the material separating the electrodes on each side of the transducer is increased,

the capacitance (such as 10a of FIG. 3) is effectively reduced; so that the resistance of the resistive electrode 30 would have to be correspondingly increased to obtain the same characteristics of the low-pass R-C filter.

5 A preferred material which has been used in constructing actual transducers of the type shown in FIG. 4 is lead zirconate/lead titanate which has a dielectric constant of 3,400. This dielectric constant is considerably higher than that of Rochelle Salt which is in the 10 range of 10 to 200.

Referring now to FIGS. 5 and 6 there is shown a variation of the transducer shown in FIG. 4, and the portions of the transducer shown in the cross-section of FIG. 6 are provided with the same reference numbers

15 used in FIG. 2 but these reference numbers are primed to indicate components in the device of FIGS. 5 and 6 which are similar to the components of the device shown in FIG. 2. The upper electrode 31 on the electrostrictive transducer driving element 12' preferably is formed by electroless plating, such as vacuum deposition or sputtering, of a uniform layer of nickel over the entire upper surface of the ceramic 12' with the ceramic 12' being a lead zirconate/lead titanate ceramic of approximately 5 mils thickness. The resistive nickel electrode, in the form of the deposited layer, has a thickness of 0.1 mils or less.

20 A deposited electrode 31 is used for several reasons. First of all, the thinnest foils normally available have a thickness of 0.3 mils extending on up to a thickness of 5 mils. Electrodes of such thicknesses made of nickel or other similar materials exhibit too high a conductivity to be used as a resistive electrode for a practical sized transducer (of the order of a diameter of 1 to 2 inches). Furthermore if a cemented foil were used for the electrode 31, a number of air spaces would be formed between the foil and low spots on the contours of the ceramic surface, causing a nonuniformity in the dielectric constants between the electrodes at different points on the electrode surfaces. To provide for the intimate bonding necessary to eliminate such air spaces so that the electrode 31 follows the finest contours of the ceramic surface of the electrostrictive driving element 12', it has been found that the electrode 31 should be a deposited film.

25 30 35 40 45 50 55 60 65 To increase the effective resistance between the center of the resistive conductor 31 and its outer edge, the conductor 31 is scribed to form a helical pattern or path from the center of the conductor 31 to its outermost edge. This scribing is shown by the groove 32 which is shown in FIG. 5 as forming eight turns or convolutions from the center to its end near the outer edge of the transducer. The spiral groove 32 is cut completely through the resistive electrode 31 to the surface of the ceramic material 12', so that the conductive path within the resistive electrode 31 from the center to the outer edge of the transducer is constrained to follow the convolutions of the spiral. Thus, the path is substantially extended over that which would be present if the spiral were not formed in the electrode 31, so that the resistance from the center to the outer edge is substantially increased for the resistive electrode 31 over that which would be present without the spiral groove 32.

In a transducer of the type shown in FIGS. 5 and 6 which has been successfully operated, the electrostrictive material 12' was lead zirconate/lead titanate having a thickness of 5 mils and a diameter of 2 inches. This electrostrictive material was prestressed and po-

larized to form a dished transducer/diaphragm. The resistive electrode 31 was made of electroless deposited nickel having a thickness of approximately 0.1 mils, and the conductor 13' covered the lower surface of the electrostrictive element 12'. The conductor 13' was made of highly conductive metal and exhibited a resistance of 4 ohms thereacross. The resistance from the center of the resistive electrode 31 to the extreme outside edge measured 420 ohms. With a two volt input applied to the terminals 16' and 17' connected to the centers of the electrodes 13' and 31, the following voltage attenuation at different frequencies measured at the extreme circumference of the transducer was found:

250 Hertz	1.95 Volts
500 Hertz	1.75 Volts
1,000 Hertz	1.40 Volts
3,000 Hertz	0.60 Volts
5,000 Hertz	0.35 Volts

The input impedance of this same device also was measured and provided the following relationships:

250 Hertz	1,400 Ohms
500 Hertz	710 Ohms
1,000 Hertz	480 Ohms
3,000 Hertz	360 Ohms
5,000 Hertz	300 Ohms

From the foregoing, it can be seen that a substantial attenuation of the input signal takes place for increasing frequencies of this signal, which is the desired result to cause only the innermost portion of the disc to be activated for operation at high frequencies. At the same time, it should be noted that at the low frequency end of the applied signal range, practically the full voltage also is applied across the electrodes at the outer edge or circumference of the disc. Thus, substantially the entire disc is activated at the lower frequency end of the applied frequency spectrum. Again, this is the desirable condition of operation.

With respect to the input impedance, it can be noted that the variation of the input impedance over the frequency range given in the chart is approximately 4.7 to 1. Similar measurements made on a transducer of comparable dimensions, but not having the resistive electrode 31, exhibited a variation in input impedance of 20 to 1 over the same input frequency range.

By driving the transducers of FIGS. 4 or 5 and 6 at frequencies above the natural resonant frequency of the transducers, only a portion of the transducers is excited, as described above; so that undesirable overtones are not generated.

A speaker system incorporating a ceramic transducer having an electrode structure of either FIG. 4 or FIG. 5 and 6 is shown in FIG. 7. The structure consists of a pair of circular drivers 33 and 34 connected together at their outer edges by a support member 36. The drivers 33 and 34 each have a pair of ceramic sheets separated by center vanes 38 and 39 respectively. The drivers also each have the electrode structure of FIGS. 4 or 5 on both sides of the driving units. If desired, the center vanes 38 and 39 would be omitted and a single sheet of ceramic used.

The center electrode 54 of the lower driver 34 is mechanically connected to the mass of the speaker frame 40 by a connecting pillar 41 to support the transducer. Speaker cone 43 is mechanically fastened to the center electrode 51 of the upper driver 33.

Each driver 33 and 34 includes a pair of outer electrodes 45 and 46, and 47 and 48 respectively and also the inner electrodes 51 and 52, and 53 and 54 respectively. The outer electrodes 45-48 are electrically connected together and the inner electrodes 51 and 52 of ceramic driver 33 are connected to the input terminal 49. Center vanes 38 and 39 are connected to input terminal 50.

Each of the ceramic drivers 33 and 34 have resistive electrodes 57 and 60 positioned between the conductive electrodes. The resistive portions of the electrodes cover the greatest portion of each of the opposing faces of the ceramic drivers and most of the driving current applied to the ceramic drivers goes through the resistive electrodes. The structure of FIG. 5 provides a speaker having a very linear response over a wide frequency range.

I claim:

1. An electrostrictive transducer including in combination, first and second driving elements each having inward and outward opposing faces at least one of which has a resistive electrode thereon, said faces of said first and second driving elements with said resistive electrodes further having central conductive electrodes and annular conductive electrodes along the periphery thereof with said resistive electrodes electrically connecting said central and peripheral electrodes, first support means for holding said first and second driving elements in spaced apart parallel relationship with said inward opposing faces being adjacent, circuit means acting to electrically connect all of said peripheral electrodes, second support means mechanically connected to the center of said outward face of said first ceramic driving element, a first electrical input/output terminal connected to said central conductive electrode of said second ceramic driving element, and mechanical load-driver means mechanically connected to the center of said outward face of said second ceramic driving element.

2. The ceramic transducer of claim 1 wherein, said first and second driving elements are formed of a pair of thin ceramic sheets with a conducting center vane positioned therebetween, and both of said opposing faces of said driving elements have resistive electrodes thereon with central conductive electrodes and annular conductive electrodes along the periphery thereof, a second input/output terminal connected to each of said center vanes, and a first input terminal connected to each of said central electrodes of said second ceramic driving elements.

3. The ceramic transducer of claim 1 and further including a loudspeaker structure including a frame and a speaker cone mounted thereon, the transducer being mounted on said loudspeaker structure to furnish the driving force therefor, said second support means being mechanically connected to said frame and said speaker cone comprising said mechanical load/driver means.

4. A transducer for operation over a predetermined range of frequencies including in combination:

a disc-shaped electrostrictive driving element formed of ceramic material, the thickness of which is substantially less than the diameter and having first and second opposing faces; a first electrode disposed on said first face, covering a major portion of the surface area thereof, and formed in a nonlinear configuration to extend the effective length of the electrically conductive path

extending from a first point located on said first face at the center thereof and a second point located on said first face near the edge thereof; a second electrode disposed on said second face of said electrostrictive driving element; and means for applying electrical signals across or for obtaining electrical signals from across said second electrode and a point on said first electrode at the center of said first face, the resistivity of at least said first electrode being sufficient to operate in conjunction with distributed capacitance in said driving element to cause the attenuation of signals at high frequencies in said range of frequencies to be several times the attenuation of signals of lower frequencies in said range.

5. The transducer of claim 4 wherein, the sheet resistance of said first electrode is uniform.

6. The combination according to claim 4 further including means for mechanically loading or mechani-

cally driving said transducer at a point substantially adjacent the center of said first face of said electrostrictive driving element.

7. The combination according to claim 4 wherein said first electrode is in the form of a spiral, the center of which is located substantially at the center of said first face of said electrostrictive driving element so that the length of the conductive path from said first point to said second point is increased by the convolutions of 10 said spiral.

8. The combination according to claim 7 wherein said first electrode comprises a deposited metallic electrode, with said spiral being formed by scribing through said first electrode to said electrostrictive disc, and the 15 resistance on the first electrode between said first and second points being greater by at least an order of magnitude than the resistance measured between a pair of comparably spaced points on said second electrode.
